UNITED STATES PATENT OFFICE.

OLIVER H. CLOYD, OF PEORIA, ILLINOIS, ASSIGNOR TO CHESTER E. WALKER, OF PEORIA, ILLINOIS.

MANIFOLD AND PREHEATER.

Application filed April 26, 1920. Serial No. 376,519.

To all whom it may concern:

Be it known that I, OLIVER H. CLOYD, a citizen of the United States, residing at Peoria, in the county of Peoria and State of Illinois, have invented certain new and useful Improvements in Manifolds and Pre-heaters; and I do hereby declare that the following is a full, clear, and exact description of the invention, which will enable others skilled in the art to which it appertains to make and use the same.

This invention relates to a combined manifold and pre-heater for internal combustion engines.

15 The invention has for one of its objects to pass the vapors moving toward the combustion chamber through a series of chambers or cavities arranged in a peculiar manner, relatively, so that said vapors and the 20 air drawn in with them will be thoroughly intermingled to produce the best possible explosive mixture.

Another object is that of interposing in 25 the path of the incoming vapors a heated baffle plate whereby the vapors are made to impinge upon the same in their travel toward the engine, thus placing the vapors in condition to produce better combustion.

Another object is that of interposing in 30 the path of the incoming vapors a member upon one side of which the vapors impinge in their travel, and upon the other side of which the heat from the exhaust manifold is made to impinge as a pre-heating agent.

35 The air drawn through the pipe 16 is necessarily heated and the suction must naturally draw the heat down upon the said bottom 13' and thus not only heated air enters the carburetor for better and more 40 quick vaporization, but the vapor when entering the shell 5 is again heated by contact with said bottom thus providing for the saving of fuel and quick response to the throttle and better engine performance.

45 In the appended drawing showing the preferred embodiment of my invention,

Figure 1 is a side elevation of my combined manifold and preheater shown in connection with a carburetor.

50 Figure 2 is a plan of portions of the manifold taken on line 2—2 Figure 1.

Figure 3 is an elevation of portions of the manifold in transverse section taken on line 3—3 Figure 1, and

55 Figure 4 is a transverse section of part

of what is shown in Figure 3 taken on line 4—4 of said Figure 1.

In the first of the figures, 1 designates a part of the engine, 2 the exhaust manifold, and 3 a carburetor.

60 My intake manifold comprises the usual branch conduits 4 abutting against and connecting with the combustion chamber, not shown.

5 is a shell, open at its top, connecting the 65 said branches 4, the latter and said shell being preferably a single casting.

6 is a conduit connected at one end with the carburetor 3 and terminating at its other end within the shell 5, there being a plate 70 7 forming a closure for the bottom of the shell, secured to the latter and carried by said conduit 6. This plate has an opening 75 through it at 8, Figure 2, and cast with said plate is a boss 9 into which is screwed a pipe 10 to communicate with said opening.

11 is a housing or hood made in two portions, adapted to be clamped together upon the exhaust manifold 2, there being an elbow 12 part of which is cast with each portion, its lower end opening into a conduit 13. This conduit terminates in a flange 14, for convenience, to which is attached the flange 15 at one end of a pipe 16 whose other end connects with the air intake of the carburetor 3, there being an opening in the pipe at 17 closed by a pivoted swinging plate 18.

80 Part of the body of the conduit 13, its bottom or lower wall, constitutes a closure for the top of the shell 5 and depending therefrom into the latter is a tubular extension 19 forming a pocket open at its lower end and spaced from the plate 7 and lying between the wall of the shell 5 and the terminus of the conduit 6, which terminus is spaced from the top of the shell 5 as already stated herein and in consequence is spaced 95 from the bottom 13' or lower wall of said conduit 13.

100 The wall of the housing 11 as shown in Figure 4 is spaced from the wall of the manifold 2, the former having a flange 20 at each end extending beyond the walls of said housing to engage said manifold for 105 spacing the walls apart.

The manifold made up of the parts 4, 5, 6 and 19 being closed to entrance of air, except through the carburetor, draws the air and vapor through the conduit 6, causing the 110

same to strike directly upon the bottom of the conduit 13, being thence deflected and drawn downward again, striking upon the plate 7, then taking an upward course through the shell 5 and out through the branches 4 to the engine.

Now, in the travel of the vapor in this tortuous manner, heavy particles of such substances as paraffine, kerosene and the like 10 will be cast upon the surfaces of the tubular extension 19 and the shell 5, as well as the under surface of the bottom 13' of the conduit 13 and upon the plate 7 which, as collected, will be drained away through the 15 pipe 10.

Due to the suction through the manifold, the hot air created around the exhaust manifold 2 is drawn to the carburetor opening through the conduit 13 and pipe 16 and in 20 its course heats the bottom 13' of the said conduit 13, upon the opposite side of which the vapor from the conduit 6 impinges as already stated, and thereby the vapor is rendered a better explosive mixture.

25 It is quite clear that since the vapor can expand into the extension 19 and again expand therefrom into the shell 5 before moving into the manifold branches 4, a thorough mixture of the air and fuel must result.

30 The wall of the conduit 13 where it closes the shell 5 is made fairly thin so as to heat quickly whereby the vapors contacting therewith will at once be affected.

Although I have illustrated a preferred 35 arrangement of my manifold, changes may be made in the construction that may be considered as coming within the invention and the claims presented herewith.

I claim:

40 1. The combination with an internal combustion engine, its carburetor and its exhaust manifold, of a closed shell, a conduit connecting the shell at opposite sides with the combustion chamber of the engine, a part 45 enclosing part of the said exhaust manifold and extending to and upon one of the other sides of the shell for conveying heat thereupon, a tubular part extending from the inner surface of the side receiving the heat 50 and terminating at its end in spaced relation to an opposite side, said part being also in spaced relation to the sides with which the conduits are connected, and a conduit connected with the carburetor and extending into the shell and into the open 55 end of said tubular part and terminating in an open end in spaced relation to the side of the shell upon which the heat is conveyed, the walls of said conduit being 60 spaced from the walls of said tubular part.

2. The combination with an internal combustion engine, its carburetor, and its exhaust manifold, of a closed shell, conduits connected into opposite walls of the shell 65 and with the combustion chamber of the

engine for conveying vapor thereto, a tubular part enclosing part of the said exhaust manifold and terminating upon one of the other walls of said shell, a tubular part within the shell depending from the last 70 named wall thereof, spaced from the first named walls and terminating in an open end remote from the conduits opening thereto, and a conduit connected to the carburetor extending into the shell and into the 75 said tubular part closely adjacent to the said last named wall.

3. The combination with an internal combustion engine, its carburetor and its exhaust manifold, of a closed shell, a conduit 80 connecting the shell at opposite sides with the combustion chamber of the engine, a part enclosing part of the said exhaust manifold and extending to and upon one of the other sides of the shell for conveying heat 85 upon the latter, a tubular part extending from the inner surface of the side receiving the heat and terminating at its end in spaced relation to an opposite side, said part being also in spaced relation to the sides with 90 which the conduits are connected, a conduit connected with the carburetor and extending into the shell and into the open end of said tubular part and terminating in an open end in spaced relation to the side of 95 the shell upon which the heat is conveyed, the walls of said conduit being spaced from the walls of said tubular part, and a drain-pipe connected into the lower side of the shell for conveying from the latter heavy 100 substances.

4. In combination with the combustion chamber and carburetor and exhaust manifold of an internal combustion engine, an intake manifold including in its construction at substantially its middle a closed shell with the side walls of which the branches of the manifold communicate near one end, a tubular portion extending from an end wall of the said shell nearest the position of the said branches and terminating in an open end near the opposite end of the shell and spaced from the walls of the latter, a conduit connected with the carburetor, extending into the shell and into the open end of the said tubular portion, and spaced from both the latter and terminating in spaced relation to the wall from which the said tubular portion extends, a part enclosing a part of the exhaust manifold and extending to the wall of the shell that lies opposite the opening of said conduit, and a pipe connecting the manifold-enclosing part and the air intake side of the carburetor. 110 115 120

In testimony whereof I affix my signature 125 in presence of two witnesses.
